ROTATABLE RECEPTACLE PIECE FOR TOY TOPS OR THE LIKE

Anthony D. Miller, Torrance, Calif., assignor to
Mattel, Inc., Hawthorne, Calif.

Filed Jan. 20, 1970, Ser. No. 20,999

Term of patent 14 years

Int. Cl. D21—02

U.S. Cl. D34—15

FIG. 1 is a top perspective view of a rotatable receptacle piece for toy tops or the like, embodying my new design;

FIG. 2 is a side elevational view thereof;

FIG. 3 is a front elevational view thereof, the rear elevational view being substantially the same;

FIG. 4 is a top plan view thereof; and

FIG. 5 is a bottom view thereof.

I claim:

The ornamental design for a rotatable receptacle piece for toy tops or the like, as shown.
